HANDLE FOR MATTRESSES AND THE LIKE

Michael Bechik, St. Paul, Minn.

Application April 3, 1943, Serial No. 481,671

3 Claims. (Cl. 16—125)

My present invention belongs to the mattress art and relates to improvements in handles for lifting, turning, and carrying mattresses and analogous furniture cushions. More specifically stated, the invention relates to the use, on mattresses and analogous furniture cushions, of pre-formed solid type handles and to the anchoring of such handles to the flexible walls of the mattress.

A specific object of the present invention is the provision of anchoring means forming a permanent part of the mattress wall and which will permit application of a pre-formed and shaped solid handle of the cast or molded variety to the mattress wall from the exterior thereof with its anchoring ends projecting through the mattress wall, and will thereafter positively lock the anchoring ends of the handle against outward displacement, but will, in case the handle is broken, permit displacement of the broken portions of the handle inwardly through the anchoring devices and the subsequent application of a new handle to the mattress wall and the locking or clamping devices from the exterior of the mattress wall.

Hitherto, it has been the accepted commercial practice to use mattress handles of the soft, very flexible, woven variety, and I, myself, have invented and commercialized anchoring devices of such highly flexible woven handles which could be readily attached to the wall of the mattress from the exterior thereof, these being disclosed and claimed in my prior art Patents 2,248,328 and 2,011,747. However, the anchoring devices of my said prior patents, while serving the purposes of permitting original application of and replacement of soft and very flexible woven handles to the mattress walls after completion of the mattress and without opening up the mattress, are not applicable for use in connection with solid and less flexible handles of the kind formed by the casting or molding of plastics.

In the preferred embodiment of the invention herein illustrated, the handles have in-turned anchoring ends or shanks and are integrally formed therewith of a suitable plastic such as "Tenite," which has limited, but, nevertheless, sufficient, flexibility, a high degree of tenacity, and a sufficient degree of ductility for the purpose, and are transparent, and, therefore, blend with and look well with mattress walls of various different color schemes. The anchoring devices employed in the preferred embodiment of the invention illustrated are of the spring teeth variety permitting insertion therethrough of a correctly sized anchoring

shank in an inward direction only and positively locking the shank against movement in an outward direction, and these anchoring devices are permanently attached to the interior of the mattress wall in alignment with cooperating apertures in the mattress wall.

In the accompanying drawing, like characters indicate like parts throughout the several views.

Referring to the drawing:

Fig. 1 is a perspective view of a bed or lounge mattress;

Fig. 2 is an enlarged fragmentary sectional view looking downwardly at an edge portion of the mattress above a mattress handle of the present invention;

Fig. 3 is an enlarged fragmentary sectional view taken on the line 3—3 of Fig. 1; and

Fig. 4 is a fragmentary detail view taken on the line 4—4 of Fig. 3.

The mattress illustrated is of the conventional variety used on beds and comprises top and bottom walls 5, side walls 6, and end walls 7, in addition to the usual resilient padding, not shown. The walls 5, 6, and 7 are shown as being formed of inner and outer layers 8 and 9 of suitable fabric with an intervening thin padding 10 of cotton or the like. As in usual practice, the inner and outer layers 8 and 9 of the mattress walls may be assumed to be stitched together to hold the intervening padding in place.

The handles of the invention are indicated as entireties by 11, and, in accordance with the present illustration, the mattress is shown as provided with two of these handles 11 on each end wall and two on each side wall. The handles illustrated are preferably formed of a plastic compound known as "Tenite," which is readily obtainable in commercial quantities, or may be formed of other plastics or other materials having qualities of flexibility, tenacity, and ductility similar to "Tenite." The handles 11, as illustrated, are circular in cross section and are integrally formed with in-turned ends providing anchoring shanks 12, and may be molded to shape, or cut from straight lengths of extruded plastic and the ends forming the shanks 12 thereafter formed by re-heating and subsequent bending.

During the process of manufacture of the mattress, suitably spaced handle shank-receiving apertures are cut in the mattress walls, and these apertures are provided with the customary reinforcing grommets 13 having out-turned annular anchoring flanges 14 and 15, the former overlying the inside of the mattress wall, and the

latter overlying the outside of the mattress wall.

In accordance with the present invention, the grommets 13 serve, in addition to reinforcing of the aperture walls, as means for permanently anchoring the clamping devices in place, and, to this end, annular lock washers 16 are telescopically applied over the intermediate tubular portions of the grommets 13 beneath the inner grommet flanges 14, and are locked, by the grommets, tight against the inner face of the mattress wall. In practice, the grommets are primarily formed only with their outer flanges 15, and the inner flanges 14 thereof are die-formed after the grommets and lock washers have been assembled on the mattress wall. Lock washers 16 are of considerably greater diameter than the flanges 14 of the grommets, and serve as extensions thereof.

The anchoring devices embodied in this preferred form of the invention are, as previously indicated, of the spring tooth variety and are in the nature of annular plates 17 having radial slots extending outwardly from their axial apertures to provide circumferentially-spaced spring teeth 18 with sharp inner ends that define the walls of the axial apertures thereof. These clamping plates 17 are primarily formed flat and with axial apertures of somewhat less diameter than that of the handle-anchoring shanks to be inserted therethrough, so that upon inward application of the handle-anchoring shanks 12 the spring teeth 18 will be deflected inwardly and will thereafter exert yielding tension on the inserted anchoring shank. Preferably, therefore, the anchoring plates 17 will be formed of spring steel or other metal having sufficient spring resilience to maintain tight frictional engagement with the interposed anchoring shank or a subsequently applied anchoring shank. In practice, the sharp ends of the clamping plate teeth 18 will engage the plastic shanks 12 with enough pressure to cut or form a permanent impression therein, and, of course, due to their inwardly deflected angles, they will positively lock the shanks against outward movement from a set position, but will, at any time, permit relatively free further movement therethrough in an inward direction, thereby permitting the inward disposition of the broken ends of a handle to the interior of a mattress and the subsequent inward application of the shanks of a new handle.

At their outer peripheries, the clamping plates 17 positively interlock with the peripheral portions of the lock washers 16 by rolling circumferentially-spaced edge portions 19 of the lock washers over the inner face edge portions of the clamping plates. In practice, it is desirable to maintain the clamping plates inwardly of the flanges 14 of the grommets, and for this purpose suitable spacing washers 20 are interposed between the lock washers and clamping plates.

The clamping plates are locked in place by a separate operation immediately following the forming of the inner flanges 14 on the grommets, and, of course, before the mattress is completed, but the handles 11 are preferably applied after the mattress is completed, and, in fact, may be applied either by the manufacturer or by the

wholesaler or retailer. In fact, the handle locking devices disclosed are so inexpensive that they may be applied to the mattresses by the manufacturer and the mattresses sold to the wholesaler or even to the retailer without handles, with a view of having the wholesaler or retailer carry a stock of these handles and apply them or not at his own discretion, depending upon the price for which he is selling the mattress. This scheme is particularly practical with the present invention when transparent plastics, such as "Tenite," are employed, since the same handles may be used for mattresses of various colors and color schemes and will appear to be of any color underlying the same.

In order to permit insertion of a broken handle through the grommet and axially aligned clamp plate aperture, it is desirable to make the internal diameter of the grommet sufficient to accommodate the curved portion of the handle, connecting the same with their anchoring shanks; and, in practice, the shanks will usually be inserted to the maximum extent permitted by engagement of the inner radius of such connecting portions with the outer ends of the grommets.

What I claim is:

1. In a mattress, a spaced pair of grommets extending through a wall of the mattress and having out-turned annular anchoring flanges on opposite sides of the wall, a lock washer applied over each grommet inside of the mattress wall and locked in place by the inner anchoring flanges thereof, a pair of clamp plates applied over the lock washer and anchored thereto at their peripheries, said clamp plates having circumferentially-spaced radially inwardly projecting spring teeth with sharp edges defining axial apertures in alignment with the axial apertures of the cooperating grommets, and a pre-formed solid handle lying along the exterior of the mattress wall and having integral in-turned ends inserted inwardly through the grommets and clamp plate apertures and in frictional locking engagement with the latter.
2. In a mattress, a spaced pair of grommets extending through a wall of the mattress and having out-turned annular anchoring flanges on opposite sides of the wall, a lock washer applied over each grommet inside of the mattress wall and locked in place by the inner anchoring flanges thereof, a pair of clamp plates applied over the lock washer and anchored thereto at their peripheries, said clamp plates having circumferentially-spaced radially inwardly projecting spring teeth with sharp edges defining axial apertures in alignment with the axial apertures of the cooperating grommets, and a pre-formed handle lying along the exterior of the mattress wall and having inwardly-directed ends inserted inwardly through the grommets and clamp plate apertures and in frictional locking engagement with the latter.
3. The structure defined in claim 2, in which the said in-turned ends of the handle are formed of relatively solid material.

MICHAEL BECHIK.
